UNITED STATES PATENT OFFICE.

BENJAMIN P. MCKINLEY, OF FLUSHING, NEW YORK, ASSIGNOR TO HEMCO ELECTRIC MANUFACTURING COMPANY, OF LONG ISLAND CITY, NEW YORK, A CORPORATION OF NEW YORK.

DESIGN FOR A PLUG CONNECTER OR SIMILAR ARTICLE.

Application filed April 29, 1925. Serial No. 13,259. Term of patent 14 years.

To all whom it may concern:

Be it known that I, BENJAMIN P. MCKINLEY, a citizen of the United States, residing at Flushing, county of Queens, State of New York, have invented a new, original, and ornamental Design for a Plug Connecter or Similar Article, of which the following is a specification, reference being had to the accompanying drawing, forming a part thereof.

Figure 1 is a side elevation of a plug connecter embodying my design; and Fig. 2 is an end elevation of the same.

I claim:

The ornamental design for a plug connecter or similar article as shown.

BENJAMIN P. MCKINLEY.
